UNITED STATES PATENT OFFICE.

JOSEPH W. PROCTOR, OF BEAUMONT, TEXAS.

FASTENING AND RELEASING DEVICE FOR LOGGING-CAR CHAINS.

980,003.

Specification of Letters Patent.

Patented Dec. 27, 1910.

Application filed September 8, 1910. Serial No. 581,011.

To all whom it may concern:

Be it known that I, JOSEPH W. PROCTOR, a citizen of the United States, and a resident of Beaumont, in the county of Jefferson and 5 State of Texas, have invented an Improved Fastening and Releasing Device for Logging-Car Chains, of which the following is a specification.

The object of my invention is to provide 10 an improved attachment for platform cars, or for trucks and wagons, for securing and releasing log-binding chains used thereon. It is requisite that the means employed shall be strong, durable, and simple in construction, and especially that they shall be adapted 15 for releasing the logging chains without danger to the operator.

My invention pertains to the chain-secur- 20 ing and releasing devices proper, one mem- ber of which may be adjusted for releasing a logging chain at such distance therefrom as to insure safety to the operator.

The details of construction, combination, 25 and operation of the invention are as here- inafter described, and illustrated in the accompanying drawing in which—

Figure 1 is a diagrammatic side view of a 30 platform logging car provided with my im- proved attachment. Fig. 2 is an enlarged side view of the attachment. Fig. 3 is a plan view. Fig. 4 is a perspective view of the casting forming part of the chain-secur- ing device.

In the several figures, 1 indicates a casting 35 having approximately the form of a rectangular oblong block, the same being provided in its face with a central lengthwise groove 2 and with lateral lugs 3 arranged opposite and separated by a space sufficient to freely 40 accommodate the links of a logging chain. The said lugs are provided with perforations 4 adapted to receive a pin 5 which constitutes the other member of the chain-fas- 45 tening and releasing device proper.

The block 1 is rigidly and firmly secured 50 to the side of a car-sill y in vertical position as shown, by means of screw-bolts 6 passing through the same at their diagonally opposite corners.

A logging chain x is secured in the manner shown in Figs. 1, 2, and 3, those links 55 which are parallel to the lugs or ears 3 ly-

ing partly in the groove 2 of the block, while the other links which are parallel to the face of the block lie free between the 55 lugs. The locking pin 5 passes through the holes 4 in the lugs and across one of the links which is parallel to the face of the block and between the two adjacent links which are parallel to the lugs 3, thus secur- 60 ing the chain as will be readily understood.

For the purpose of operating; that is to say, withdrawing the pin 5 and thus releas- 65 ing the chain, at a safe distance from the fastening, and also to provide a sufficiently powerful means for the purpose, I employ a rod 7 and hand-lever 8, the latter being ar- 70 ranged horizontal and pivoted at 9 to the car sill. The rod is pivotally connected with a short rigid upwardly projecting arm 70 8^a of the lever, and its other end is piv- 75 oted to the pin 5. By pulling the lever han- dle downward, it is obvious the pin 5 may be withdrawn from the lugs 3, thus releasing the chain x without any danger to the op- 80 erator. For greater safety, the levers of the two respective chains employed on a car or other transporting vehicle are arranged ad- 85 jacent to the ends of the platform as shown in Fig. 1. The free or handle end of lever 8 is supported when not in use by a loop 10 which is pivoted and adapted to swing lat- 90 erally, so as to adapt it to receive and re- lease the lever.

As shown, the left-hand lug or ear of the 95 block 1 is made thicker than the opposite lug, since it bears more of the strain incident to fastening and releasing the chain.

What I claim is:—

1. The improved apparatus for the pur- 90 pose specified, comprising a casting having opposite perforated lugs on its face side and a lengthwise groove extending between and parallel to said lugs, a pin adapted for in- 95 sertion through the lugs for fastening a chain in the manner described, a rod connected with said pin, and a pivoted hand- lever with which said rod is connected, as shown and described.

2. The combination with the platform of 100 a transporting vehicle, of a casting secured thereto in vertical position and provided with a lengthwise groove and opposite perforated lugs, a pin adapted for insertion

through the lugs, and a slidable rod and pivoted lever connected therewith for operating said pin in the manner described.

3. In an apparatus for the purpose specified, the combination with a perforated casting having a vertical groove to receive a chain, of a pin adapted to traverse said groove, a rod pivoted to the pin, a lever

pivoted and arranged normally horizontally, and having a lateral arm to which the rod 10 is pivoted, as shown and described.

JOSEPH W. PROCTOR.
